UNITED STATES PATENT OFFICE

2,186,580

SEALED RECEPTACLE

Edward H. Fabrice, Chicago, Ill.

Application June 22, 1938, Serial No. 215,185

6 Claims. (Cl. 220—54)

The present invention relates to improvements in sealed receptacles of the type wherein the sealing means must be severed into two parts in order to effect unsealing of the receptacle.

Generally, a structure of this type comprises a receptacle equipped with a severable sealing cap equipped with means for tearing out a ribbon of metal between the ends of the cap, or wherein the lower end portion of the cap is severed from the crown portion, said lower end portion being sometimes crimped over a bead on a bottle as in the patent to Stattmann No. 1,481,035 and in other instances is engaged with a stop formation on a bottle for preventing rotation of the threaded crown portion of the cap until said lower end portion of the latter is either severed from the crown portion and thus disengaged from the stop formation, or a portion of the lower skirt portion of the cap is removed to permit rotation of the remainder of the cap to effect unsealing of the receptacle.

The general state of the art is fairly exemplified by the patents to Fabrice Nos. 1,771,034, 1,798,151 and 2,056,778. The patent to Hothersall No. 1,981,864 is also referred to.

It has been common practice in all-metal receptacles of the perforated top type to secure the perforated top to the body of the receptacle after filling the latter with comminuted material by friction as by making the inner dimensions of the peripheral flange of the cap slightly less than the outer dimensions of the portion of the receptacle body to be embraced by said flange and then forcing the cap into place, the same being then non-removable without distortion of the cap or receptacle body. The patent to Hothersall is exemplary of a cap of this type which, however, includes means for severing the crown portion of the cap from the portion of its flange which is held by friction upon the receptacle body.

The main object of the present invention is to provide an all-metal receptacle and sealing cap for the same wherein a portion of the cap which is severable from the crown portion of the cap cooperates with a formation of the receptacle to seal the latter hermetically, and wherein, after the removal from the cap of the sealing portion of the same, an immediately adjacent portion of the cap cooperates with the said formation of the receptacle to reseal the latter as in the case of ordinary slip-cover cans and the like, commonly employed for packaging baking powder and other products.

The present invention may be said to constitute an improvement upon the structure of the last-mentioned patent in the particular structural characteristics and advantages hereinafter pointed out.

In the accompanying drawing illustrating an exemplary embodiment of the invention,

Fig. 1 is a side elevation of a sealed receptacle constructed in accordance with the invention.

Fig. 2 is a fragmentary central vertical section of the same taken on the line 2—2 of Fig. 1.

Fig. 3 is a view similar to Fig. 2 showing the sealing cap in its initial position preparatory to forcing the same into sealing position upon the receptacle.

Fig. 4 is a plan sectional view taken on the line 4—4 of Fig. 1.

Figs. 5 and 6 are fragmentary detail sectional views on an enlarged scale further illustrating the structure.

The invention is designed particularly for embodiment in receptacles composed of thin sheet metal such as aluminum or an aluminum alloy, though it is equally adaptable to receptacles made of other metals.

In the instance illustrated, the receptacle 1 is of the seamless type and of generally cylindrical form, this form being best adapted for certain specific uses of the receptacle, wherein it is desired or required to maintain an appreciable degree of fluid pressure or vacuum within the same. Generally, the requirement is to maintain a relatively high degree of vacuum within the receptacle for preservation of the contents thereof.

Preferably the receptacle 1 is provided between its ends and more proximately to its open mouth than its bottom, with an outwardly extending bead 2 of appreciable length axially of the receptacle and having all points in its surface parallel with the axis of the receptacle and continuously convex about said axis without presenting any irregularities in its peripheral surface, the latter being required to be smooth and convex throughout at all points.

The closure cap 3 conforms in shape generally in plan section with the plan sectional shape of the receptacle 1, its lower end portion being expanded to greater plan sectional dimensions than its crown portion, said lower end portion presenting an outwardly projecting bead consisting of three integrally associated portions 4, 5 and 6.

The portion 6 comprises a relatively narrow ring of metal of inner lateral dimensions substantially equal to the outer lateral dimensions of the bead 2 and which receives the latter telescopically and relatively snugly when the cap 3 is first mounted upon the receptacle, as shown in Figs. 3 and 6.

The portion 5 is offset inwardly from the portions 4 and 6 a distance substantially equal to one-half the thickness of the metal of which the cap is composed and is of slightly smaller internal lateral dimensions than the outer lateral dimen-

sions of the bead 2 over which it is forced to effect sealing of the receptacle.

This offsetting of the portion 5, which also comprises a relatively narrow ring of the metal, is effected by shearing the metal along the meeting points of the portions 4 and 5 in a plane perpendicular to the axis of the cap and provides an easily fracturable connection 7 between the portions 4 and 5. The offsetting of the portion 5 from the portion 6 is effected by the ogee curved bead formation 8. A similar bead formation 9 is provided to connect the portion 4 with the crown portion of the cap 3, the portion 4 being shown as constituting the lower terminal of said bead 9.

15 As shown in Fig. 1, a shear cut 10, of L-shape is cut through the portion 6 from its lower edge vertically to a point in the lower terminal of the bead 8 and along said terminal of the bead 8 and along said terminal to define a tongue 11 which 20 may be easily engaged by a finger nail and bent outwardly for engagement between finger tips.

From the inner end of the severance cut 10, a scoring groove 12 extends angularly over the bead 8 and portion 5 and connects with the shear cut 25 7 at a point spaced an appreciable distance from the inner terminal of the severance cut 10. The groove or scoring 12 is formed entirely in the outer face of the metal to render the latter easily severable along said groove.

30 After the receptacle is filled, the cap 3 is disposed upon the same in the position shown in Fig. 3, and is then forced down to the position shown in Figs. 1 and 2, thereby effecting expansion of the portions 4, 5 and 6, as shown in Figs. 35 2 and 5, and also expanding the portion 4, attention being directed to the fact that the bead 9 is relatively long and thus will expand readily without imposing undue stress or strain on the shear-cut 7 which remains intact.

40 The expansion of the portions 4, 5 and 6 necessarily places appreciable stress upon the scoring groove 12 and tends to sever the portion 5 along the same, but the angular disposition of this scoring groove 12 causes the stress thereon to be exerted more longitudinally than transversely thereof and thus its fracture is prevented. However, the said stress renders the severance of the metal along said groove very appreciably easier than would otherwise be true and thus the 45 said groove may be of less depth than is ordinarily required, and the strength necessary to prevent fracture under the influence of the aforesaid expansion thus preserved.

45 It will be noted that the shear-cut 7 is disposed below the upper edge of the bead 2 when the cap is in its sealing position, as shown in Figs. 2 and 5, so that it is well supported, this being advantageous in effecting severance along said shear cut 7.

60 The expansion of the portion 6 spaces the latter sufficiently from the bead 2 to enable a finger nail to be inserted between the tongue 11 and said bead to bend the said tongue outwardly as above noted, said tongue being thus maintained flush 65 with the remainder of the portion 6.

65 It will be noted further by reference to Figs. 3 and 6 that the shear cut 7 is made in a cylindrical portion 13 of the flange of the cap 3 some distance below the bead 9 which is vertically aligned 70 with the terminal portion 6 and is also expanded coincidentally with the expansion of the portion 5 so that when the cap is severed along the shear-cut 7, the said portion 4 will contract to its initial diameter and hug the bead 2 of the receptacle.

75 cle snugly, but not with sufficient force to prevent easy removal of said cap.

It will be noted that there is a free annular space between the upper portion of the flange of the cap 3 above the bead 9, and the neck portion 5 of the receptacle 1, the purpose of said space being to permit the cap to become self adjusted relatively to the receptacle as the cap is forced into sealing position, the initial or ultimate position of the cap relatively to the receptacle being 10 sometimes slightly eccentric of the latter.

If said annular space were not provided, then the stress on the shear cut 7 would not be uniform throughout and would cause it to become fractured along that portion which is subjected to 15 the greatest stress. To further guard against variations in stress, the annular portion 6 of the cap acts as a guide or lead member cooperatively with the bead 2 to cause the cap to move down axially parallel with the receptacle so that the 20 offset portion 5 will be expanded uniformly as the cap is forced into sealing position.

Similarly, if the said shear-cut 7 is disposed above the bead 2, it is more apt to fracture responsively to lateral pressures on the cap than 25 when it is opposed to the bead 2. The said shear-cut 7 is designed to provide a very easily fracturable connection between the opposite ends of the cap so that the latter will sever readily and accurately responsively to manipulation of the 30 tongue and leave no part of the strip or portion 5 connected with the cap.

The sealed receptacle above described will withstand twelve or more pounds fluid pressure within the receptacle and will maintain a correspond- 35 ing degree of vacuum within the same.

I claim as my invention:

1. A receptacle equipped with a uniformly smooth, peripheral surface portion parallel with its axis, a flanged cover equipped in its flange with an inwardly offset peripheral formation conforming to the cross-sectional shape of said smooth surface and of slightly smaller lateral dimensions than the latter, a shear-cut extending partially through the metal of said cover peripherally of said flange in a plane perpendicular to the receptacle axis and bordering the upper edge of said formation, the terminal end portion of said flange being of substantially the same inner lateral dimensions as the outer lateral dimensions of said receptacle surface portion and adapted to receive the latter snugly telescopically and offset outwardly from the lower end of said formation of said cap a distance substantially equal to the depth of said shear cut, a digitally engageable tongue severed peripherally out of said terminal end portion of said cover flange and free from the latter along three edges with its lower edge flush with the lower edge of said flange, and a scoring groove connecting the said tongue with said shear-cut, said formation of said flange adapted to be forced over said surface portion of the receptacle and expanded thereby, the unsealing of the receptacle being effected by severance of all of the portion of said flange lying 50 below said shear-cut from the cap along said shear-cut.

2. A receptacle equipped with an outwardly projecting peripheral bead presenting an outer surface of appreciable length parallel with the receptacle axis, a cover equipped with a peripheral flange having a terminal portion adapted to snugly and telescopically receive said bead, a peripheral portion of said flange between its ends being offset inwardly from the said terminal por- 75

tion and being of slightly less lateral dimensions than said receptacle bead and adapted to be forced over the latter and thereby expanded to seal the receptacle, a peripheral continuous shear-cut in a plane perpendicular to the axis of the cover and receptacle and of a depth less than the thickness of the metal of the cap bordering the upper edge of said offset portion and lying over said bead when the cap is in sealing position, a tongue completely severed from said lower terminal portion except at its inner end and having its lower edge flush with the lower edge of said flange, and a metal weakening groove disposed in the outer surface of the flange and extending 10 angularly from said shear-cut to the inner upper end of said tongue, said terminal portion of said flange being expanded substantially coincidentally with said offset portion and rendering said tongue digitally engageable to effect severance of the metal along said groove and said shear-cut for complete removal of all of said flange lying below said shear-cut to render the cap removable 20 from the receptacle.

3. A receptacle equipped with an outwardly projecting bead presenting an outwardly convex surface of appreciable length parallel with the receptacle axis, a peripherally flanged cover having its lower end portion offset outwardly from its upper end portion to provide a lower terminal 25 skirt portion of dimensions to snugly and telescopically receive said bead, another peripheral portion of said skirt portion disposed above said terminal portion and of less length than said bead being offset inwardly from said terminal portion a 30 distance less than the thickness of the metal of said flange and providing a peripheral strip of smaller lateral dimensions than said terminal portion and said bead adapted to be forced over the latter and be thus expanded and become disposed 35 between the ends thereof to seal the receptacle, a continuous peripheral shear-cut bordering the upper edge of said strip and disposed in a plane perpendicular to the axis of said cap and receptacle and presenting a downwardly facing 40 shoulder, there being a substantially L-shaped slot in said terminal portion of said flange having one arm thereof extending from its lower edge to a point between its ends and its other arm extending peripherally of said terminal portion, and an external groove extending from the 45 inner end of the last-named arm of said slot angularly across said strip in a direction away from said slot to a point in said shear-cut.

4. A receptacle equipped between its ends with an outwardly projecting bead of appreciable length presenting a peripherally convex surface parallel with the receptacle axis, a sealing cap equipped with flange extending over said bead for sealing said receptacle, said flange equipped 50 with a terminal portion adapted to snugly telescopically receive said bead, an inwardly offset portion of slightly smaller diameter and less length than said bead, a peripheral shear-cut in a plane perpendicular to the cap axis bordering the upper edge of said strip, the portion of said cap immediately above said shear-cut being normally adapted to telescopically receive said bead, the said receptacle having a neck portion embraced by the upper end portion of said cap and 55 being of smaller diameter than the latter, there being a slot in said terminal portion of said flange defining a digitally engageable arcuate tongue, there being a groove extending from said slot angularly to the said shear-cut for causing 60 all of the portion of the cap below said shear-cut

to be severed from the cap responsive to manipulation of the tongue, the said offset portion adapted to be forced over said bead to be disposed between the ends of the same and spaced from its upper edge, the terminal portion of said flange constituting a lead for said flange and the same and the portion of the cap immediately above said shear-cut being expanded simultaneously with said offset portion and thereby spaced from said bead and said portion above said shear-cut being self-contracting following severance of the cap along said shear-cut for cooperation with said bead for substantially sealing the receptacle. 10

5. A sheet metal receptacle equipped between its ends with a peripheral outwardly projecting bead formation of appreciable length and presenting an outer surface parallel with the axis of said receptacle, a closure cap equipped with a peripheral flange receiving the said bead and including a portion of less lateral dimensions than said bead disposed entirely upon the surface of the latter in expanded relation thereto and cooperating therewith to hermetically seal the receptacle, a peripheral shear cut of less depth than the thickness of the metal of said flange disposed in a plane perpendicular to the cap axis and extending inwardly from the outer surface of said flange and bordering the upper edge of said smaller dimensioned portion of said flange constituting a means for effecting severance of the latter from the body of the flange, a bead formation between said shear-cut and the extremity of said flange parallel with and spaced from said shear-cut cooperating with the latter to define said smaller dimensioned portion of said cap, said portion equipped with a metal weakening groove of greater length than the width of said portion extending angularly across the same and through said last-named bead formation and connecting said shear-cut with one end of a slot extending 20 to the lower extremity of said flange. 30

6. A receptacle presenting an outwardly continuously convex surface parallel at all points with the receptacle axis and equipped between its ends with an outwardly offset peripheral bead 45 of appreciable length also presenting a continuously convex outer surface parallel at all points with the receptacle axis, a closure cap having its skirt portion corresponding in shape substantially with the outer surfaces of said receptacle and said bead for snugly receiving telescopically the portion of said receptacle above said bead, the lower end portion of said cap skirt being of larger lateral dimensions than the upper end portion thereof and equipped between its ends with a continuous peripheral shear-cut of less depth than the thickness of metal of which said cap is composed and overlying said bead, the portion of the cap skirt below said shear-cut being offset inwardly from the portion above the latter, and said inwardly offset portion being of slightly less lateral dimensions than said bead and adapted to be forced to embracing relation to the latter for hermetically sealing the receptacle, said inwardly offset portion equipped with an external metal weakening groove extending angularly downwardly from a said shear-cut to a point spaced from the lower extremity of said cap skirt, the latter equipped with a substantially L-shaped 50 slot extending upwardly from its extremity to a point spaced from said shear-cut and thence substantially parallel with the latter to the lower end 55 of said groove.
